UNITED STATES PATENT OFFICE.

HARVEY N. DAVIS, OF CAMBRIDGE, MASSACHUSETTS, ASSIGNOR TO RESEARCH CORPORATION, OF NEW YORK, N. Y., A CORPORATION OF NEW YORK.

APPARATUS FOR RECTIFICATION OF AIR.

Original application filed July 7, 1920, Serial No. 394,544. Divided and this application filed November 17, 1920. Serial No. 424,760.

To all whom it may concern:

Be it known that I, HARVEY N. DAVIS, a citizen of the United States, residing at Cambridge, in the county of Middlesex and 5 State of Massachusetts, have invented certain new and useful Improvements in Apparatus for Rectification of Air, of which the following is a specification.

The present invention relates to air liquefaction and distillation processes and to apparatus such as is now commonly used for 10 the separation of pure oxygen or nitrogen, or mixtures rich in oxygen or nitrogen, from the atmosphere, and more particularly 15 to those parts of such apparatus which are commonly called columns or stills. The object of the invention is to make apparatus of the said kind more efficient, to reduce the power required to effect the separation 20 of a given amount of useful product, and to decrease the cost of the useful product, which may be either oxygen or nitrogen of any useful degree of purity, or both.

It should be understood that my invention, at least in some of its aspects, is applicable to apparatus for the separation of 25 mixtures other than air, which liquefy at low temperatures, and that, in describing my invention with particular reference to 30 the separation of air, I am not limiting myself to reference to this particular application of it.

For a full understanding of the invention reference is had to the accompanying drawings, in which—

Figs. 1 and 2 are diagrams introduced solely for expository purposes.

Figs. 3, 4 and 5 are diagrams representing 40 various alternative arrangements of rectification apparatus or of parts thereof embodying the various elements of the invention in alternative forms.

Before describing specific embodiments of 45 the invention, I desire to explain certain underlying fundamental principles, an understanding of which will make the details of the various alternative embodiments much easier to follow. There are four fundamental principles that have guided the 50 design of all the alternative arrangements proposed. These four principles are:—

I. The main rectification train should be run substantially at atmospheric pressure,

and should be fed with as much unliquefied and substantially uncompressed air as possible.

II. Adequate means should be provided for transferring heat to or from the contents of the main rectification train at all levels, or, if this be impracticable, at a plurality of well distributed levels, and not merely, as is substantially the case in the present state of the art, at the top and bottom.

III. Appropriate streams of fluid of different compositions should be fed into the main rectification train at as many different, well distributed levels as possible, so as to minimize the heat transfer requirements mentioned in II.

IV. There are certain levels in a rectification train designed in accordance with I, II, and III at which longitudinal heat leakage is especially detrimental, while at other levels it is much less detrimental, and may even be desirable to a certain extent. The structure containing the rectification train, may, therefore, advantageously be divided into two or more parts, connected by relatively slender metal parts, in such a way as to minimize longitudinal heat leakage at those particular levels where it is most detrimental.

These four principles may be further explained as follows:

I. The rectification train should be run substantially at atmospheric pressure and should be fed with as much unliquefied and substantially uncompressed air as possible.

I am well aware that there are certain advantages in running the main rectification train under a much higher pressure, in that it is not then necessary to maintain temperatures as low as those which must exist in a low pressure rectification train, and in that the greater densities of the gaseous fluids handled means a more compact column for a given output, both of which considerations indicates that a high pressure rectification train will have smaller heat-leak losses than a low pressure train.

On the other hand, running the main rectification train under pressure is justified from the power standpoint only when a considerable part of the work required for compression is recovered in some useful

form, as in at least one system previously patented. But unfortunately the efficiency of compressors and expansion engines is such that the increased losses in these machines will much more than overbalance the increased losses due to heat-leak in a low pressure system. The essential feature of such a system is that as large a part as possible of the air to be rectified shall be fed 5 not only into the main rectification train itself, but also into the system as a whole, at the lowest possible pressure, that is to say at a pressure above atmospheric by just enough to keep this air in motion through 10 the system against atmospheric pressure at the various outlets, and to admit of means for controlling this flow. According to my invention the only air that is materially compressed at all is that amount which will just suffice, under the most effective arrangements 15 that can be devised, to furnish the heat-pumping power required to keep the system in operation.

II. Adequate means should be provided 20 for transferring heat to or from the contents of the main rectification train at all levels, or at a plurality of well distributed levels and not merely, as is substantially the case in the present state of the art, at the 25 top or bottom or both.

This proposition, which is of great importance, can best be explained by reference to Figs. 1 and 2. Fig. 1 represents diagrammatically a rectification train of the simplest possible type. Unliquefied air enters 30 the train through the pipe 1, gaseous nitrogen, of any desired purity, leaves the top of the train through the pipe 2, and liquid oxygen of any desired purity leaves the train through the pipe 3. The interior of the shell 4 may be filled with a large number of trays of any well known type, or with baffles, glass beads, hollow aluminum balls, or any other well known structures, 35 whereby a stream of gas rising through the shell under a slight pressure gradient, is brought into intimate thermal and physical contact with a stream of liquid descending through the shell under the action of gravity. That space in a column in which 40 an ascending stream of gas and a descending stream of liquid intermingle and interact, together with the structure containing and controlling the streams will be referred 45 to throughout the specification and the claims as a rectification train, as distinguished from the column itself which may and usually does contain, aside from the rectification train or trains, other structural elements or groups of elements participating 50 in the process of rectification. It is assumed that at every level the compositions of the gaseous and liquid streams are such 55 as to be in equilibrium with each other in accordance with the well known laws of

two-phase binary mixtures, and the experimental facts represented by the well known Baly curves and other similar experimental data. We assume further that the temperature at the various levels in the train 70 varies uniformly with height from that appropriate to orthobaric, nearly pure oxygen liquid at substantially atmospheric pressure, at the bottom of the train, to that appropriate to saturated, nearly pure nitrogen vapor at substantially atmospheric pressure, at the top. And finally we assume that the air inlet pipe 1 is at that level at which the rising gaseous stream in the train has the composition of air. 80

We then enquire under what conditions this rectification train could theoretically be operative in the manner assumed. Let us consider any level PQ in the lower part of the train, at which the temperature is T. There 85 will be a stream of liquid flowing down past this level containing, say, m mols of oxygen and n mols of nitrogen. There will also be a stream of gas flowing up past this level, containing, say, M mols of oxygen and N mols of nitrogen. To determine these four quantities, m , n , M and N as functions of the temperature we have the four conditions; 1st, that the ratio of m to n must be such as to give the liquid composition 90 corresponding to T on an oxygen-nitrogen two-phase equilibrium diagram such as Baly's curve; 2nd, that the ratio of M to N must be such as to give the gaseous composition corresponding to T on an oxygen-nitrogen two-phase equilibrium diagram such as Baly's curve; 3rd, that $(m-M)$ 95 must be equal to the quantity of oxygen leaving the train at the bottom; and 4th, that $(n-N)$ must be equal to the quantity of nitrogen leaving the train at the bottom. 100 If the flow and composition of the desired oxygen-rich product are assumed, these four relations completely determine m , n , M and N as functions of T throughout the lower part of the train. Similar considerations 105 determine them in the other parts of the train. The results of a typical case are plotted approximately to scale in Fig. 2. 110 In this case, the quantity of liquid that must be flowing down past each level in the train, must vary from level to level in substantially the manner shown by the graph *a* in Fig. 2, in which horizontal distances represent mols and vertical distances represent either 115 temperatures, or heights in the rectification train of Fig. 1, and in which, as is common in theoretical discussions, the rectification is assumed to be distributed continuously over the height of the train. This graph *a* of Fig. 2 shows that in a theoretically perfect rectification train of the type described, the quantity of matter in the descending liquid stream must be zero 120 at the top of the train and must increase, 125 130

at first very rapidly, and then more slowly, until the stream reaches the air inlet level 1 of Fig. 1. From this level down, the quantity of matter in the descending liquid stream must decrease, at first with some rapidity, then more slowly, and finally with considerable rapidity to a value at the bottom of the train that represents the quantity of nearly pure liquid oxygen leaving the train through the pipe 3 of Fig. 1. From this it is evident that there must be condensing action all through the upper part of the train down to the level 1, and vaporizing action all through the part of the train below the level 1. This means that heat must be withdrawn from the contents of the main rectification train at all levels above the level 1 and that heat must be imparted to the contents of the main rectification train at all levels below the level 1, if the train is to function in the ideal manner assumed above. The amount of heat that must be transferred either to or from the contents of the train at the various levels is indicated approximately by the graph A of Fig. 2, in which areas to the right or left of the vertical reference line represent heat units to be transferred within the corresponding temperature intervals in the train.

It is therefore obvious that if a train of the type of Fig. 1 is to be made to operate in the assumed manner, means must be provided for effecting the necessary heat transfers at the various levels. This is best done by auxiliary streams of fluid which it is desirable, or at least thermodynamically permissible, to warm or cool as the case may be. Two such streams of fluid are obviously available, even in the simple train represented in Fig. 1. One of these is the stream of cold nitrogen product from the top of the train, which is, in the present state of the art usually carried direct to the much warmer interchanging system. This stream should be carried down through coils or other passages in intimate thermal but not physical contact with the contents of the rectification train, at least as far as the level 1 of Fig. 1, so that its heat absorbing power, which is available through the coldest and therefore most unmanageable temperature range in the whole apparatus may be made use of in the most effective possible way, namely in helping solve the heat-removal problem inherent in the upper part of the main rectification train.

Furthermore the air entering the train through the pipe 1 has left the main heat interchanging system at a temperature substantially equal to that appropriate to the bottom of the main rectification train, and its power to give up heat as it cools from this temperature to that appropriate to the level 1, is available throughout the tem-

perature range below the level 1 in the main rectification train. This stream 1 of low pressure air may therefore advantageously be passed through coils or other passages in intimate thermal but not physical contact with the contents of the main rectification train through the whole or a considerable part of that portion of the train below the level at which it enters the train. 70

Several other advantageous means of 75 transferring heat to the contents of the lower part of the main rectification train will be described in later parts of these specifications, including streams of high pressure air which it is desirable to cool, 80 streams of intermediate pressure air which it is desirable to cool and partly or wholly condense, and streams of nitrogen which it may be desirable either to condense or merely to cool. Each of these means will 85 be mentioned in connection with another specific feature to which it is appropriate, but it should be understood that each has also the novel and great advantage of playing its appropriate part in effecting the 90 necessary transfer of heat into the lower part of the main rectification train. 95

Certain advantageous means will also be described in detail later for taking heat out of the upper part of the main rectification train by means of streams of fluid in thermal but not physical contact with the contents of the main train at various levels thereof. In particular it is sometimes advantageous to form substantially pure nitrogen liquid in a manner to be described later, and to pass a part of this liquid through coils or other passages and evaporate it in thermal but not physical contact with the contents of the main rectification train at various levels between the level 1 and the top of the train. It is also sometimes advantageous, as will appear later, to form other liquids richer in nitrogen than the liquid in the main rectification train appropriate to the level 1 in Fig. 1 and to pass parts of these liquids through coils or other passages and partially evaporate them in thermal but not physical contact with those portions of the main rectification train between the level 1 and the levels at which the partially evaporated liquids may appropriately be mingled with the streams in the main train. 100 110 115

Each of these procedures has great advantages over putting the streams of liquid directly into the main train at levels below those to which their compositions are appropriate. Each has also certain advantages, in some cases, over putting the whole of each stream into the train at its appropriate level for reasons that will appear later. These procedures are mentioned here as examples of ways in which heat can be abstracted from the upper part of the main 120 125 130

rectification train by cold streams of fluid other than the stream of nitrogen product mentioned above.

III. The type of rectification train shown diagrammatically in Fig. 1 could doubtless be made operative by the means described above, but the amount of necessary heat transfer is large and, particularly in the upper part of the train, difficult to effect in a practical manner. It is therefore advantageous to modify the rectification train itself by introducing streams of fluid other than the single stream of gaseous air represented in Fig. 1 as entering through the pipe 1. In all such modifications it is a fundamental thermodynamic principle that each stream should enter the main train only at that particular level to which its composition is appropriate. To secure the best results in minimizing the necessary heat transfer for ideal operation, or, in other words, to so modify the ideal heat transfer curve A of Fig. 2, that it shall lie as nearly along its vertical base line as possible, it is desirable that such streams as enter the train above the low pressure air inlet level 1 of Fig. 1 shall be wholly or largely liquid, and that such streams as enter the train below the low pressure air inlet level shall be wholly or largely gaseous. Means for providing gaseous or largely gaseous streams of appropriate composition for entrance below the level 1 are described in a copending application of Davis and Kleinschmidt Serial No. 394,545 filed July 7, 1920. Means for providing liquid or largely liquid streams of appropriate composition for entrance above the level 1 will now be described.

The most important liquid or largely liquid stream that can be fed into the upper part of a rectification train, is a stream of pure or nearly pure liquid nitrogen at the top of the train. Such a stream is already commonly used in the art. It is formed by some (see for example U. S. Patents No. 1,201,044 and No. 1,257,470) by supplying under pressure a stream of previously purified nitrogen, which is cooled in an interchanger, condensed by thermal interchange with a pool of the liquid oxygen discharged from the bottom of the rectification train, and then throttled in to the uppermost part of the train. This procedure may however be improved in two ways. In the first place the pool of liquid oxygen fed from the bottom of the train is not the best available place to condense this nitrogen, as this is the warmest part of the column or still, and the pressure under which the nitrogen stream is supplied must therefore be higher if it is to be condensed in this way, than would be necessary if condensation is effected in other and cooler parts of the train. A better way of condensing a stream of nitrogen for use

at the top of the train, and, if desired, for cooling the whole of the upper part of the train in the manner described in a previous paragraph of these specifications, is to pass this nitrogen stream through coils or other passages in thermal but not physical contact with the contents of that part of the main rectification train that lies just below the low pressure air inlet level 1 of Fig. 1, the pressure of the nitrogen being just sufficient to cause condensation under these much more favorable conditions. This procedure has also the advantage of giving heat to the contents of the main rectification train in a region where, according to graph A of Fig. 2, the desirable heat transfer rate is materially larger than at somewhat lower levels. Furthermore, under these conditions the nitrogen stream can be cooled in coils or other passages in thermal but not physical contact with the contents of the whole lower part of the train, with the double advantage of promoting the condensation of the nitrogen, and supplying heat to the contents of the main train at all levels below the level 1 of Fig. 1, in the manner previously mentioned.

With some dispositions of the rest of the apparatus, the stream of nitrogen mentioned in the last paragraph may be important not only as supplying wash-liquid for the uppermost part of the rectification train, but also because of its potential heat pumping power. Under these conditions it is desirable to pass it to the column under a higher pressure than that contemplated in the last paragraph. If, however, the pressure of this stream is raised only moderately above that necessary to secure condensation before the stream leaves the lower part of the column, either condensation with latent heat absorption, or abnormally high specific heats will appear in the main interchanger system, with the disadvantageous results described in my Patent No. 1,420,625 granted June 27, 1922. Under these conditions, the said stream of nitrogen may well pass through the interchanging system and enter the column or still, at or near its lower end, under a pressure that is materially above the critical pressure of nitrogen, and pass up through the whole lower part of the rectification train in coils or other passages in thermal but not physical contact with the contents of the train, thereby giving heat to the contents of the train at all levels below the level 1 of Fig. 1, and being itself cooled substantially to the temperature appropriate to the level 1 without any condensation whatever. When this stream of "high pressure" nitrogen is throttled from the level 1 into the top of the main train, liquid will be formed abundantly.

A second method of providing the nitrogen required to form the said liquid stream, also well known in the art (see for example

U. S. Patent No. 981,748) consists in so treating a stream of air under pressure as to leave a gaseous residue which is nearly pure nitrogen, and subsequently condensing this 5 nitrogen substantially in the manner described above. This procedure has a considerable advantage in that a separate nitrogen compressor and a separate supply of previously purified nitrogen are not necessary. This procedure, as now known to the 10 art, can, however, be much improved by the application of the fundamental principles already described in these specifications. For example, since the process of condensation 15 and rectification that goes on in the ascending or "backward return" tubes in the lower part of the well known Claude column, requires the removal of a considerable quantity of heat at all levels, and since the process that goes on in the lower part of the 20 ideal rectification train of Fig. 1 requires the absorption of heat at all levels, it is obvious that each process will be furthered by putting it in thermal but not physical contact 25 with the other. This means that the ascending or "backward return" tubes of the well known Claude column should be in thermal contact not merely with a single boiling off pool at the bottom of the column 30 as in U. S. Patent No. 981,748, or even with two or three such boiling off pools as in U. S. Patent No. 1,083,988, but with the contents of the whole lower part of the main rectification train from the bottom thereof up to 35 the lowest level at which any material to be rectified enters the train; that is to say, the Claude "backward return" tubes should be surrounded by, instead of merely surmounted by, the trays of the lower portion of the 40 main rectification train, in a manner to be described later in connection with Fig. 5.

It is also obvious that, because of the shape of the ideal heat transfer graph A of Fig. 2, and in particular because of the fact 45 that the amount of heat that should be given to the contents of the main rectification train at levels just below the low-pressure air inlet level is greater than at somewhat lower levels, it will be advantageous in some dispositions of apparatus, for example that shown in Fig. 5, to make the nitrogen condensing tubes much shorter than the backward return tubes, or to replace them by coils or other passages surrounding only the 55 upper part of the backward return tubes, so that their heat yielding power may be concentrated in a part of the main rectification train where it can be used to the best advantage.

60 Other means for forming from air under treatment the nitrogen desired for the upper part of the column will be described in later paragraphs of these specifications.

65 The effect of a stream of liquid nitrogen, introduced at the top of the main rectifica-

tion train, on the ideal heat transfer graph for the upper part of the train, is shown by graphs b and B of Fig. 2. The introduction of a certain amount of nearly pure nitrogen liquid will just suffice to reduce to zero 70 (or preferably to the magnitude of the inevitable heat leak into this part of the apparatus) the amount of heat transfer required to maintain the uppermost part of the ideal rectification train of Fig. 1 in operation, but the effect on the ideal heat transfer requirements at levels just above the low pressure air inlet is small.

If a considerably larger quantity of nearly pure liquid nitrogen is introduced, conditions are modified as in graphs c and C of Fig. 2. A considerable quantity of heat should now be put into the uppermost levels of the train, and if this heat is not supplied by special means or by heat-leak, the whole 80 uppermost part of the train will cool toward a uniform temperature, and the rectification effect will be crowded down toward the low pressure air inlet until the longitudinal heat-leak in that part of the column is sufficiently increased to provide the necessary heat. That is, the uppermost part of the train, will be drowned with liquid. If, therefore, an excess of nitrogen liquid is available, it is not desirable to put all of it into 85 the top of the train as is now commonly done in the art. It is much more advantageous to throttle a part or all of it into coils or other passages scattered through the whole upper portion of the main rectification train, and particularly in regions thereof just above levels at which streams enter the train, as in Fig. 4, so that a part of the 90 said nitrogen liquid may be evaporated by heat withdrawn from the contents of the main train at these levels, and so that the quantity of liquid actually entering the uppermost part of the main rectification train may be not greatly in excess of the amount needed to make the desirable heat 95 transfer rate there equal to the inevitable heat-leak rate.

If other liquids, richer in nitrogen than the liquid appropriate to the level 1 of Fig. 1, are available, and are introduced in appropriate quantities, each at the level to which its composition is appropriate, the effect on the ideal heat transfer curve of the upper part of the train is very marked. Each stream reduces the desirable heat 100 withdrawal rate at the levels immediately below its point of entry, and may make an input of heat desirable just below its point of entry. Indeed if a very great number of such streams of appropriate magnitudes and compositions could be provided, the ideal heat transfer curve could be made to substantially coincide with its vertical baseline, or preferably with the line representing the inevitable heat-leak distribution.

Even under practical conditions several such streams can be fed into the upper part of a rectification train of the type herein described with great advantage. I am well aware of the fact that the use of a plurality of such streams of liquid has been described by others, notably by Claude in the aforementioned U. S. Patent No. 1,083,988, but never, 10 to my knowledge, in connection with a stream of unliquefied or gaseous air, such as that represented as entering the train of Fig. 1 through the pipe 1, and it is this combination of a plurality of liquid streams 15 with a lower gaseous stream which is most advantageous.

I have furthermore, provided improved methods of forming one or more of these streams other than the uppermost or nearly 20 pure nitrogen stream previously discussed.

In particular one such stream is especially easy to form. If a stream of air under pressure is wholly liquefied, either by the process described by Claude in U. S. Patent No. 967,104 and elsewhere, or in coils or passages in thermal but not direct contact with a pool of liquid oxygen fed from the lower end of the main rectification train, as is common in the art, the resulting liquid must 25 have the composition of air, and even after it has been throttled to the pressure in the main train, with some inevitable accompanying evaporation, the remaining liquid will be much richer in nitrogen than the liquid 30 appropriate to the level 1 in Fig. 1. Such a stream is therefore highly suitable for use, in the manner described above, at a suitable point in the upper part of a rectification train of the type under discussion. Nevertheless, 35 such a stream has never, as far as I am aware, been used to supplement the gaseous air and liquid nitrogen streams mentioned above.

The process by which the stream mentioned above, and all other streams herein mentioned as entering the main rectification train at levels above the low pressure air inlet level 1 of Fig. 1, are formed may advantageously be modified as follows. It is 45 obvious that if such streams can be further cooled after liquefaction but while still under pressure, the inevitable partial re-evaporation that accompanies throttling will be reduced, and the remaining liquid will be richer in nitrogen. Means for effecting this 50 further cooling in the main interchanger have already been described by others, and in particular by Claude in U. S. Patent No. 967,104. But inasmuch as no one has apparently been aware hitherto of the desirability 55 of imparting heat to the contents of the main rectification train at all levels below the lowest level at which material enters the train, no one has, as far as I am aware, 60 seen the desirability of still further cooling 65

all liquid streams of the sort under consideration, by passing them through coils or other passages in thermal but not physical contact with the contents of the main rectification train throughout the region below 70 the lowest level at which material enters the train.

It will be seen later that in the disposition of apparatus represented by Fig. 5, this improvement might well be applied to all 75 three streams of liquid entering the upper part of the main rectification train, although no means for accomplishing it are actually represented in the figure, lest the said figure become too complicated for easy 80 comprehension. The same is true of certain other streams in other possible disposition of apparatus and the scope of this part of my invention should not be understood to be limited to those particular cases in 85 which I have found it convenient to show it in the accompanying drawings.

It is at least theoretically desirable to supply to the upper part of the main rectification train as many largely liquid streams 90 of different compositions as possible, and additional streams of suitable composition can be formed in a variety of ways. In particular, the familiar Claude backward return tubes, either in their usual form, or in the modified disposition shown in Fig. 5, can be further modified, with advantage, by separating each of them into two or more successive and superposed portions, with 95 means for collecting at various levels the liquid formed in the portions of the tubes immediately above each said level, and means for passing these liquids, which will be successively richer in nitrogen, into the 100 upper part of the main rectification train, each at its appropriate level. A somewhat similar arrangement is described in Claude's U. S. Patent No. 1,083,988, but the arrangement here proposed has two considerable 105 advantages. In the first place, since the tubes should, as has been mentioned, extend up through the whole lower part of the rectification train, much cooler temperatures are available for the later parts of the rectification than in his disposition of apparatus, and so the pressure inside the backward return tubes can be somewhat reduced. And in the second place, all portions of the tubes in my arrangement contain upward 110 flowing gaseous streams, so that rectification by backward return is effective in all parts of the apparatus instead of merely in alternate sections of the tube system, as in Claude's disposition of apparatus in the 115 U. S. patent referred to.

IV. We now turn to the last of the fundamental principles mentioned in the first part of these specifications. A rectification train designed in accordance with the principles already discussed will be fed by two 120

or more streams of material, at least one of which will enter the train at a point intermediate between its highest and its lowest level. The rectification train may therefore be regarded as divided by these levels at which material enters it, into two or more portions, each of which will hereinafter be called a run of the train, each run being a portion of the train within which there is no level at which material enters the train.

If the amounts of material entering the train in each stream are wisely adjusted, each run except the lowest will have an ideal heat transfer curve such that heat should be supplied to the contents of the run at all higher levels thereof, and heat should be abstracted from all the lower levels thereof. In the lowest run heat should be supplied at all levels, no matter how the streams are adjusted. It follows that all regions just above, or colder than, a level at which material enters, should be losing heat, and all levels just below, or warmer than each such level should be receiving heat. But the tendency of the inevitable longitudinal heat-leakage in the train is, in the immediate neighborhood of each such level, exactly opposed to the ideal state of affairs just mentioned. The upper part of each run, which should be gaining heat, will lose heat by longitudinal transfer to the lower part of the next higher run, which in its turn will gain this heat, when properly it should be losing heat. It is therefore precisely at those levels at which material enters a rectification train, that longitudinal heat-leak is most undesirable. I therefore propose as a new and useful improvement in the design and construction of a rectification train, that it be divided structurally into two or more separate portions at one or more of the levels at which material enters it, that these portions be insulated from each other as well as from their surroundings in the most effective practicable way, and that such pipes and other connections between successive portions of a rectification train as may be necessary, be so arranged as to provide as small an opportunity for the leakage of heat as may be practicable. For the sake of simplicity I have shown only one such division, the principle being the same irrespective of the number of divisions. This division of the main rectification train into two or more structurally distinct portions may also have certain other advantages, which will be mentioned later in connection with Fig. 4.

Within any one of the upper runs of a rectification train, the effect of longitudinal heat-leak is quite different. The lower or warmer levels of such a run should ideally lose heat, and the upper or cooler levels should ideally receive heat, and this is pre-

cisely what longitudinal heat-leakage accomplishes. No unusual precautions are therefore necessary to prevent longitudinal heat-leak within any one run of a rectification train, and it is even conceivable that under some circumstances it might be desirable to encourage longitudinal heat-leak within a single run by the introduction of copper rods or the like, if other and better means for securing the desired transfers of heat are for some reason impracticable.

A much better way of ensuring appropriate heat transfer in any one of the upper runs of a rectification train is the following. Each such run should, as has been mentioned, receive the full benefit of the cooling or heat absorbing power of the stream of nitrogen product from the top of the still, over the temperature range corresponding to the run in question. But in a thermally well balanced run, only the lower levels need to lose heat. Therefore it is advisable to bypass the nitrogen product stream past the upper levels of the run and to concentrate its whole heat absorbing power, over the temperature range in question, into the lower levels of the run from which heat should be abstracted.

Furthermore the various streams of liquid that are to be throttled into the upper part of the main rectification train have been described as passing, while still under pressure through coils or other passages in thermal but not physical contact with the contents of the main train through the whole length of the lowest run thereof. It now appears that each of these streams may also be passed, while still under pressure, through coils or other passages in thermal but not physical contact with the upper levels of each run up to the level at which each said stream is to enter the main train, with advantage both to the liquid streams themselves, which it is desirable to cool as much as possible before they are throttled, and to the main rectification train, to which it is desirable to impart heat at the particular levels in question.

Having now described the fundamental principles which underlie my system or process for separating air or other gaseous mixtures into the constituents thereof, and having mentioned many of the novel and useful features thereof, I will describe as briefly as possible three alternative embodiments of some or all of the features of my invention and explain the operation thereof, pointing out in connection with each, such novel features particularly in construction or mode of operation, as have not already been mentioned.

Fig. 3 represents diagrammatically an interchanger 11 and a main rectification train contained in a shell or column 12. The in-

terchanger which is more particularly described in my Patent 1,420,625 carries three down-going streams 13, 14 and 15 composed, respectively, of L. P. air, H. P. air and H. P. nitrogen, and two up-going streams, 16 and 17 of products from the column or still. It may be stated here that pressures not materially higher than atmospheric pressure will be throughout referred to as "low pressures" (L. P.), pressures well above the critical pressures of the fluids in question as "high pressures" (H. P.), and pressures materially higher than atmospheric pressure and below the critical pressure as "intermediate pressures" (I. P.).

Three expansion engines 18, 19 and 20 fed by H. P. fluids, are provided in accordance with the principles described in my said application. In this particular case the coldest engine 20 is a nitrogen engine and exhaust I. P. nitrogen which is used in the still after the well known method of Hazard-Flamand. The other two engines 18 and 19 receive H. P. air from one duct 14 of the interchanger into which it is forced by a suitable compressor or compressors and exhaust L. P. air into another duct 13 as indicated.

The main rectification train in the column 12 consists of three runs defined by the level of the inlet 28 through which L. P. gaseous air is introduced into the column, and by the level of the inlet 44 at which H. P. air is throttled into the column after being so cooled as to liquefy almost completely at the throttle 44'.

Each of these streams is put in thermal contact with the contents of the lower run up to the level of the low-pressure air inlet 28 by being passed through the coils 30 and 40, respectively. Additional heating power for the lower run and additional cooling power for the lower portions of the two other runs are provided by utilization of the H. P. nitrogen stream.

From the interchanger 11 part of the H. P. nitrogen stream 15 is carried by pipe 15' to the coils 43 in the lower run. This stream is then, in this particular instance, divided and throttled through the valves 48 and 49 into the coils 46 and 47 respectively in the lower portions of the two upper runs. The remaining portion, if any, of this H. P. nitrogen stream is throttled through the valve 50 into the top of the main train.

The nitrogen product from the top of the column or still passes through the pipe 24 into and through the coils 25 and 26 to the bottom of the rectification train, being thereby warmed substantially to the temperature appropriate to the bottom of the interchanger to which it passes through the pipe 17', and being thereby caused to yield to the contents of the main train all of its available

cooling power, which is thus used for the purposes described above, and to assist in keeping the train cold in the face of the various inevitable heat-leaks.

The oxygen liquid leaving the main rectification train at the bottom thereof is deflected by the diaphragm 31 into the well 32 where it comes into thermal contact with a part of the I. P. nitrogen in the coil 33 and is subjected to a final purification by boiling, the intensity of which is regulated by one of the hand valves 37. The liquid oxygen then passes through the trap 34 into the outer boiling-off pool 35 where it is vaporized by heat exchange with the I. P. nitrogen in the coils 36 which are connected by pipe 20', with the exhaust side of the engine 20.

The gaseous oxygen product then leaves the still through the pipe 16'. In the meantime the largely or wholly liquefied I. P. nitrogen from the coils 33 and 36 is throttled into the top of the main train through the valves 37, the riser 38 and the valve 39.

Starting up such an apparatus as that represented diagrammatically in Fig. 3 might present certain difficulties with respect to the supply of nitrogen for the high pressure stream 15 during the period while the apparatus is cooling down and beginning to function. This period might last several hours, and it is obvious that if the stream 15 must be supplied for several hours from a reserve of nitrogen accumulated from a previous run of this or another nitrogen producing apparatus, very large and expensive storage facilities might have to be provided.

Let us suppose that the stream 15 is started with air drawn from the initially warm region 23 at the top of the still through the pipes 24, 25 and 26, etc. and finally the interchanger 11. As the system cools down, a part of this air will be liquefied by the time it again reaches the space at the top of the still. Furthermore, the ascending column of gas or vapor in the still will begin to drop some liquid before it reaches the space 23. Since both of these liquefied portions will be richer in the less volatile constituent (here oxygen), than the streams from which they are formed, the remaining gaseous streams reaching the space 23 will be richer in the more volatile constituent (here nitrogen) than when they passed their respective compressors. The stream 15, which is continually fed from the space 23 will thus grow richer in the more volatile constituent (here nitrogen). It is possible that this progressive purification of the contents of the space 23, from which stream 15 is fed, will proceed rapidly enough to keep pace with the settling of the rest of the apparatus into its steady state.

If this proves not to be the case, I propose two alternatives, each of which involves only moderate storage facilities for pure nitrogen accumulated in a previous run.

5 The first depends on the fact that the slow part of this progressive purification will be the last part, after the contents of the space 23 are nearly pure, but not quite pure enough to give the best results of which the 10 apparatus is capable. I then propose to shift temporarily the source of the stream 15 from the space 23 (via the interchanger) to the stored supply of pure nitrogen. This will supply to the space 23 through the 15 valve 39 an abundant supply of pure nitrogen liquid, which will gradually wash oxygen out of the ascending column of gas in the still, and force the upper part of the still into the desired steady state. This 20 requires a storage of nitrogen only sufficient to supply the stream 15 while the out-going stream 17 is settling into its final pure or nearly pure state.

It is possible that even this accelerated 25 process of progressive purification of the stream 17 will be too slow from the point of view either of convenience or of expense. If this proves to be the case, I propose the following, more far-reaching alternative, 30 indicated in Fig. 4. Here the still or column is separated into two parts at a point corresponding to the level of inlet 28 in Fig. 3, and means are provided whereby the ascending column of gas or vapor in the 35 lower part of the still may be diverted at the level of inlet 28 and returned through the pipe 55 to the up-going stream 16 in the interchanger system, without traversing the upper part of the still at all. At such 40 times, the valve 57' may be partly closed to maintain an appropriate pressure gradient in the lower run. Meanwhile the upper part of the still is filled with pure nitrogen from a stored supply, and this 45 nitrogen is circulated through the out-going system of pipes 24, 25, etc. to 17, compressed, and returned as the stream 15, any necessary makeup being taken from the stored supply. The effect of continuing this 50 process will be to cool the whole upper part of the still to the temperature appropriate to the space 23, and to store in it an accumulation of pure or nearly pure nitrogen liquid, without losing any considerable part 55 of the reserve of pure or nearly pure nitrogen saved from previous runs. When the storage of liquid nitrogen in the upper part of the still is sufficient, the up-going gaseous stream from the lower part of the still 60 is gradually diverted from its temporary to its final course by opening the valves 56 and 57' and closing the valve 57, and liquid from the upper part of the still is gradually admitted to the lower part of the still by 65 opening the valve 58. The necessary read-

justment of temperatures throughout the still will then take place quickly, without any material contamination of the pure or nearly pure nitrogen leaving the space 23.

The apparatus represented diagrammatically in Fig. 4 differs from that shown in Fig. 3 also in other respects. The stream of nitrogen product coming from the top of the still and passing into the pipe 24 and through the coils 25 is withdrawn from the 70 still shell approximately at the L. P. air inlet level, through the pipe 53 and is caused to cool the L. P. air from the temperature at which it leaves the interchanger, substantially to that appropriate to the L. P. air 75 inlet level, in a small auxiliary interchanger comprising passages 52 and 54 for the nitrogen and the L. P. air respectively. The arrangement of Fig. 3 is preferred, but I have chosen to draw Fig. 4 in this way chiefly 80 to avoid an unnecessarily complicated diagram.

Furthermore the liquid nitrogen cooling coils 47' in the upper runs of the train are here represented as being connected in series 90 rather than in parallel and as being fed from the main liquid nitrogen riser 38 to which they are connected by the pipe 38' and as discharging directly into the upper part 95 of the train.

Furthermore in Fig. 4 such additional nitrogen liquid as may be required for refrigeration or liquid-level maintenance in the upper part of the main train, is represented as being trottled through the valve 50 100 directly into the I. P. nitrogen exhaust pipe 20' from the engine 20, and as passing through the coils 33 and 36 with the rest of the I. P. stream.

All these will be recognized as merely 105 alternative embodiments of the same fundamental principles embodied in the apparatus shown in Fig. 3.

As clearly indicated, the rectification train and the shell containing it are divided into 110 two separate units at the level of the L. P. air inlet. Thermal relation is substantially eliminated and may exist in so far only as the necessary communications therebetween make an absolute thermal separation impossible. By suitable lagging, however, such incidental heat exchange may be reduced to a negligible quantity. During the cooling 115 down process described above, the H. P. air is throttled into the upper part of the lower unit through the valve 60 and enters the train together with the L. P. air cooled in the auxiliary cooler. After running conditions are established the H. P. air is passed by pipe 60' into and through coils 40' and, 120 after being cooled in the lower run is fed through pipe 41 and throttle valve 42 into a region of the upper unit to which its composition is appropriate. Under running 125 conditions, gaseous communication between 130

the lower unit and the upper unit takes place through the pipe 56', and liquid communication takes place through the pipe 58'.

The apparatus represented diagrammatically in Fig. 5 is a column of the familiar Claude type so modified as to incorporate the more important features of my invention.

The trays 61 of the lower run of the main rectification train are in thermal contact with backward return pipes 62 or the nitrogen condensing pipes 63 or both. The liquid from the liquefier is kept separate from that collected in the receiver 64 at the bottom of the column and is fed into the column through the pipe 65 and the valve 66 at a higher level than that at which the liquid from the receiver 64 enters the train through the pipe 67 and the valve 67'. The nitrogen product is withdrawn from the top of the train through the pipe 68 and the coils 69 so that its heat absorbing power may be used in the upper runs of the train.

Unliquefied and substantially uncom-
25 pressed air is cooled first in the main inter-
changer (not shown) and then in the auxiliary interchanger 70 and fed into the main train through the pipe 71 at a level below that at which the liquid from the receiver 64
30 enters the train. The construction shown in Fig. 3, in which the two passages of the interchanger 70 are incorporated in the lower part of the column, is perhaps preferable to that shown, and could be used in connection
35 with this disposition of apparatus.

It is evident that in this modification of a Claude column the backward return portion of the apparatus should be so designed and run as to give, in the receiver 64, not a liquid containing as little nitrogen as possible, but one intermediate in composition between the 21 to 25% oxygen liquid discharged from the valve 66 and the 47 to 49% oxygen liquid appropriate to the level of the L. P.
45 air inlet 71 so that the four streams entering the main rectification train at and above the level 71 may be as well distributed as possible.

The various possibilities for subcooling
50 the three liquid streams entering the upper part of the main rectification train that have been described above, are not illustrated in the drawing to avoid undue complexity, but I wish to have it understood that I consider
55 this aspect as within the scope of my invention.

In the following formulation of the elements of my invention, I wish certain expressions, which are used as convenient abbreviations for much longer expressions, to be understood in each and every case to have the meanings assigned to them in this and the following paragraphs. The word "rectification" shall be understood to refer to any operation wherein a stream of a gase-

ous mixture, moving from a warmer to a colder region, and a stream of liquid, moving in the opposite direction, are brought into intimate physical as well as thermal contact with each other, so that either material or heat can pass freely from one stream to the other. I am well aware that the word is used by some authorities in a more restricted sense; I desire, however, that in this specification and the accompany- 70
75 ing claims, it be understood to refer to any operation meeting the above very general definition, including operations in which either material or heat or both is added to or withdrawn from either or both streams 80 in other ways than by transference between the two streams.

It is further desired that the words "train" and "rectification train" be understood to refer either to a space which is intended to contain two interacting streams of the kind mentioned above, or to the walls, baffles, trays, etc. intended to confine and control the said streams, as the context may indicate; but not to any space intended to 90 contain any other stream or material, or to any pipe, passage, chamber, or other structural element that may be contiguous to a rectification train, or contained within the same structure or column that contains a 95 rectification train. In particular, it is desired that the words "train" and "rectification" train shall not be understood to include a boiling-off pool, such as is often placed immediately below the bottom of a 100 train in the known art, or a condenser, such as is often placed immediately above the top of a train in the known art, unless it shall appear that rectification is intended to take place in one or the other of these structures 105 to an extent materially greater than that necessarily incidental to their primary functions as initiators of the gaseous and liquid streams in the train itself.

Reference will be made in the accompany- 110 ing claims to "passing" or "introducing" material or a stream of fluid "into" a train. It is desired that neither the liquid reflux from a condenser immediately above the top of a train nor the gaseous efflux from a boiling-off pool immediately below the bottom of a train shall be regarded as one of the streams explicitly mentioned in the appended claims as "passed" or "introduced" "into" 115 the train. In other words, I wish it understood that the streams referred to in the claims are streams different from either of those just mentioned.

It is desired that the letters L. P., when applied to a fluid or to a train, shall mean 125 that the pressure of the fluid or that of the contents of the train is in the usual case substantially the same as the pressure of the atmosphere, or greater than atmospheric pressure only by such an amount as might 130

- reasonably be provided to secure adequate flow through the various parts of the separation, and to permit appropriate control of the said flow. If, however, it be desired 5 to run the whole separation apparatus with a discharge pressure greater than atmospheric so that the useful product may be passed directly to some other apparatus not a part of the separation apparatus or of the 10 power recovery apparatus primarily associated therewith, then it is desired that the letters L. P. be understood to refer to a pressure equal to or only slightly greater than the desired discharge pressure, as explained above. It is desired that the letters 15 L. P., when similarly used, be understood to define the pressure as materially greater than that defined above as L. P., but less than the critical pressure of the fluid in question. It is desired that the letters 20 H. P., when similarly used, be understood to define the pressure as materially greater than the critical pressure of the fluid in question.
- 25 This application is a division of my co-pending application Serial No. 394,544, filed July 7, 1920.
- I claim:
1. The combination with an L. P. rectification train of means for introducing material at a plurality of levels and means for abstracting heat from the contents of the train at levels just above each level other than at the top at which material is introduced into the train. 30
  2. The combination with a rectification train of means for abstracting heat from the contents of the train between the top of the train and the lowest level at which material is introduced, said means terminating its effective thermal contact with the contents of the train above or substantially at said level and means for imparting heat to the contents of the train between the bottom 35 of the train and the lowest level at which material is introduced into the train, said means terminating its effective thermal contact with the contents of the train below or substantially at said level. 40
  3. The combination with a rectification train of means for abstracting heat from the contents of the train at a plurality of different levels between the top of the train and the lowest level at which material is introduced, said means terminating its effective thermal contact with the contents of the train above or substantially at said level and means for imparting heat to the contents of the train at a plurality of different levels between the bottom of the train and the lowest level at which material is introduced into the train, said means terminating its effective thermal contact with the contents of the train below or substantially at said level. 45
  4. The combination with a rectification train of means for abstracting heat from the contents of the train at substantially all levels between the top of the train and the lowest level at which material is introduced, said means terminating its effective thermal contact with the contents of the train above or substantially at said level and means for imparting heat to the contents of the train at substantially all levels between the bottom of the train and the lowest level at which material is introduced into the train, said means terminating its effective thermal contact with the contents of the train below or substantially at said level. 50
  5. The combination with a rectification train, of means for cooling an L. P. stream of a gaseous mixture, means for introducing the cooled gaseous stream into the train intermediate the ends thereof, and means for bringing material in thermal but not physical contact with the contents of the train for abstracting heat from said contents between the top of the train and the level at which the gaseous stream enters, said last named means terminating substantially at said level. 55
  6. The combination with a rectification train, of means for cooling an L. P. stream of a gaseous mixture, means for introducing the cooled gaseous stream into the train intermediate the ends thereof, and means for bringing material in thermal but not physical contact with the contents of the train for abstracting heat from said contents at a plurality of different levels between the top of the train and the level at which the gaseous stream enters the train, said last named means terminating substantially at said level. 60
  7. The combination with a rectification train, of means for cooling an L. P. stream of a gaseous mixture, means for introducing the cooled gaseous stream into the train intermediate the ends thereof, and means for bringing material in thermal but not physical contact with the contents of the train for abstracting heat from said contents at substantially all levels between the top and the level at which the gaseous stream enters, said last named means terminating substantially at said level. 65
  8. The combination with a rectification train, of means for cooling an L. P. stream of a gaseous mixture, means for introducing the cooled gaseous stream into the train intermediate the ends thereof, means for bringing material in thermal but not physical contact with the contents of the train intermediate the top thereof and the level at which the gaseous stream enters and terminating substantially at said level, for abstracting heat from said contents, and means for bringing material in thermal but not physical contact with the contents of the train below or substantially at said level. 70

the train intermediate the bottom thereof and the level at which the gaseous stream enters and terminating substantially at said level, for imparting heat to the contents of the train.

9. The combination with a rectification train, of means for cooling an L. P. stream of a gaseous mixture, means for introducing the cooled gaseous stream into the train intermediate the ends thereof, means for bringing material in thermal but not physical contact with the contents of the train at a plurality of levels between the top thereof and the level at which the gaseous stream enters and terminating substantially at said level, for abstracting heat from said contents, and means for bringing material in thermal but not physical contact with the contents of the train at a plurality of levels between the bottom thereof and the level at which the gaseous stream enters and terminating substantially at said level, for imparting heat to the contents of the train.

10. The combination with a rectification train, of means for cooling an L. P. stream of a gaseous mixture, means for introducing the cooled gaseous stream into the train intermediate the ends thereof, means for bringing material in thermal but not physical contact with the contents of the train at substantially all levels between the top thereof and the level at which the gaseous stream enters and terminating substantially at said level, for abstracting heat from said contents, and means for bringing material in thermal but not physical contact with the contents of the train at substantially all levels between the bottom thereof and the level at which the gaseous stream enters and terminating substantially at said level, for imparting heat to the contents of the train.

11. The combination with a rectification train, of means for introducing an L. P. stream of a gaseous mixture into the train intermediate its ends, said means including means terminating substantially at the level of the point of entrance of said stream for passing the stream upwardly in thermal but not physical contact with the contents of the train at a plurality of successively higher levels between the bottom thereof and the said point of entrance.

12. The combination with a rectification train, of means for introducing an L. P. stream of a gaseous mixture into the train intermediate its ends, said means including means terminating substantially at the level of the point of entrance of said stream for passing the stream upwardly in thermal but not physical contact with the contents of the train at substantially all levels between the bottom thereof and the said point of entrance.

13. The combination with a rectification train of means for passing a gaseous product from the top of the train into thermal but not physical contact with the contents of the train below the top thereof, without material change in the pressure of the product.

14. The combination with a rectification train of means for passing a gaseous product from the top of the train into thermal but not physical contact with the contents of the train at a plurality of successively lower levels below the top thereof, without material change in the pressure of the product.

15. The combination with a rectification train of means for forming a stream of liquid under pressure, means for reducing the pressure of the said stream, and means for then putting the said stream in thermal but not physical contact with the contents of the train at a plurality of levels between the top of the train and the lowest level at which material is introduced into the train.

16. The combination with a rectification train of means for forming a stream of fluid under pressure, means for putting the said stream in thermal but not physical contact with the contents of the train at a plurality of levels between the bottom of the train and the lowest level at which material is introduced into the train, means for reducing the pressure of the said stream, and means for then putting the said stream in thermal but not physical contact with the contents of the train at a plurality of levels between the top of the train and the lowest level at which material is introduced into the train.

17. The combination with a rectification train, of means for cooling an L. P. stream of a gaseous mixture, means for passing the said gaseous stream into the train intermediate the ends thereof, means for passing a plurality of largely or wholly liquid streams into the train at different levels above the level at which the gaseous stream enters the train, and means for bringing material in thermal but not physical contact with the contents of the train between the top thereof and the level at which the gaseous stream enters for abstracting heat from the said contents, said last named means terminating substantially at said level.

18. A rectification train composed of two thermally separated sections, means for passing liquid from the bottom of the upper section into the top of the lower section, and means for passing gas from the top of the lower section into the bottom of the upper section.

19. A rectification train composed of a series of thermally separated sections, means for passing liquid from the bottom of each but the lowest section into the top of the next lower section, and means for passing gas from the top of each but the highest

section into the bottom of the next higher section.

20. Apparatus as defined in claim 18 and means for passing a stream of fluid into the train at a level adjacent to the level of thermal division.

21. Apparatus as defined in claim 19 and means for passing streams of fluid into the train at levels adjacent to the different levels of thermal separation, respectively.

22. Apparatus as defined in claim 21 and means for bringing cold products from the top of the coldest section of the series immediately into thermal but not physical contact with the contents of the train at a level or levels near the bottom of one or more of the sections.

23. Apparatus as defined in claim 21 and means for imparting heat to the contents of the train at a level or levels near the top of 20 one or more of the sections.

24. Apparatus as defined in claim 21, said last mentioned means including means for putting one or more of the said streams of fluid under a pressure higher than that in 25 the train, means for putting said streams into thermal but not physical contact with the contents of the upper part of each of one or more of the sections of the train, and means for reducing the pressure of the said 30 streams before they enter the train.

In testimony whereof I affix my signature.

HARVEY N. DAVIS.
